HYDRAULIC POWER LIFT

Edward A. Johnston, Chicago, Ill., assignor to
 International Harvester Company, a corpora-
 tion of New Jersey

Application May 22, 1935, Serial No. 22,888

20 Claims. (Cl. 97—50)

The present invention relates generally to farm tractors for propelling, carrying, and operating agricultural implements, and more specifically to power operated lifting devices.

5 The fundamental object of the invention is to provide improved mechanism mounted on the tractor driven by power derived from the engine for lifting, lowering or otherwise adjusting implements, such as plows and cultivators, attached 10 to or operated by the tractor.

More specifically, one object of the invention is to provide a power lift mechanism which is hydraulically actuated. Another object subsidiary to said object is to provide an improved and 15 simplified two-way acting hydraulic mechanism.

Another object is to provide a hydraulic mechanism which may be constructed to move an operating lifting shaft through substantially more than a half revolution, whereby the crank may 20 be connected to lifting members to move past dead center in either of two positions.

Another object is to provide a hydraulic lifting mechanism particularly adapted to the oscillation of a crank or rockshaft for use in lifting implements.

25 The above objects and others, which will be apparent from the detailed description to follow, are accomplished by the mounting of a hydraulic mechanism of a construction which may 30 be designated as a vane type, the vane being mounted in a chamber for oscillation through an angle of substantially more than 180 degrees. The lifting member in the form of a crank or rock-shaft is connected to and moved by the 35 vane of the mechanism. A hydraulic pump is mounted on the tractor in any suitable position for supplying operating liquid to the hydraulic mechanism. A suitable control valve and properly located conduits are provided for delivering 40 the high pressure liquid to either side of the vane and for allowing the escape of liquid simultaneously from the other side of the vane. In order to provide a mechanism in which the supply of high pressure liquid is rendered ineffective after 45 the vane has completed its stroke, valve means are utilized which are automatically operable by movement of the vane into its respective positions of rest at the ends of its strokes in each direction.

In the drawings,—

50 Figure 1 is a side elevation of a tractor with one wheel removed and with a portion of the transmission casing being broken away to show the installation of and driving mechanism for the liquid pump of the hydraulic lift, a portion of a 55 directly connected implement being shown at the

rear of the tractor and a forwardly extending lifting beam being shown extending toward the front of the tractor;

Figure 2 is a plan view of the rear end of the tractor shown in Figure 1, particularly showing 5 the power lift mechanism;

Figure 3 is a rear view of the rear end portion of the tractor shown in Figure 1, and of the power lift mechanism mounted thereabove;

Figure 4 is an enlarged plan view of the central 10 portion of the power lift mechanism shown in Figure 2 with the top of the valve chamber in horizontal cross-section and with a portion of the casing broken away to show the liquid chambers and the vane or piston chamber of the hy- 15 draulic mechanism;

Figure 5 is a vertical section taken on the line 5—5 of Figure 4;

Figure 6 is a vertical section along the line 6—6 20 of Figure 4;

Figure 7 is a vertical section taken on the line 1—7 of Figure 4; and,

Figure 8 is an enlarged detail, showing the vane 25 of the hydraulic lift, the two lifting shafts, and the connection between the shafts, including the supporting means for the vane.

Only a portion of a tractor has been shown, as such tractor may be of any of the conventional types used for operating farm implements. The tractor illustrated shows diagrammatically a 30 frame 10 connected to a rearwardly located casing 11, which houses the transmission and differential of the tractor driving mechanism. The rear end 12 of an engine is shown and other parts of the tractor, such as the gasoline tank 13 and the steering wheel 14. The operator's seat 15 is connected at a forward point in order to provide sufficient space for mounting the power lift mechanism directly over the rear axle of the tractor.

Laterally extending axle housings 16, rigidly 40 secured to the sides of the housing 11 at the rear thereof, form lateral supports for the driving axles 17 on which the traction wheels 18 are mounted. Suitable flanges 19 on the housings 16 provide means for attaching supports for 45 implements, such for example as the supporting bars 21 to which rearwardly extending implement beams 22 are connected. Said beams are illustrated as carrying spring shanks of a type on which cultivator shovels may be conventionally mounted. Rearwardly extending supporting bars 23 are also shown connected to the flanges 19. At the rear end of each of said bars a bell-crank lever 24 provides means for lifting and lowering the implement beam 22 through a lifting link 25. 55

Connections between the bell-crank member 24 and the power lifting device will be later described in connection with said device.

The housing 11 of the tractor shown is constructed with an open top over which a cover-plate is normally secured. For mounting the power lift device constituting this invention, said cover-plate is removed and a specially constructed cover-plate 26 is substituted therefor. Said 5 cover-plate, which is preferably constructed from a casting, carries a forward bracket on which the operator's seat 15 is mounted. At the rear of the casting, a base 27 is formed, on the upper surface of which the power lift casing 28 is securely fastened by a plurality of cap-screws, as 10 illustrated.

The power lift casing 28 is cored to form at the rear end a high pressure fluid inlet chamber 29 to which liquid under pressure is supplied 15 by a conduit 30 connected with a pump casing 31. The pump casing 31 is secured to the rear of the casing 11 of the tractor, being substituted for a cover-plate regularly supplied over a comparatively small opening at the rear of 20 the housing. Said pump casing includes a gear pump consisting of gears 32, one of which is mounted on a shaft 33 extending through a projecting boss 34 into the interior of the housing 11. By means of a train of gearing of conventional design, said shaft is driven from the power take-off shaft 35 extending longitudinally of the tractor at the bottom of the housing 11. The only change required in the usual power 25 take-off shaft is the addition of a driving gear 36, which is keyed on the shaft for engagement with the train of gears for driving the pump shaft 23. The pump casing 31 and the gears carried thereby are of a size and are so mounted that the entire unit may be removed through the rear opening in the housing 11, over which the casing is secured. The power take-off shaft 35 may be utilized with the pump in place, or removed.

A low pressure return conduit 37 connects the 30 low pressure side of the pump with a reservoir 38 formed in the casing 28. The details of the pump have not been shown, as it is of any well known conventional construction, being of a capacity sufficient to deliver liquid in the quantity 35 and at the pressure required for operating the lifting device.

A substantially semi-cylindrical chamber 39 is formed at one side of the casing 28, being open 40 at one side for assembling the component parts 45 into position. A cover-plate 40 is formed to fit over the open side and to form a liquid-tight joint therewith. Said cover-plate also carries a laterally extending sleeve 41, through which an operating shaft 42 extends. An aligned operating 50 shaft 43 extends through a bore formed in the casing 28 and a laterally extending sleeve. The portions of the shafts within the chamber 38 are best shown in Figure 7. Said shafts are formed with enlarged cylindrical end portions 55 which are secured together against rotation by pins 44, as shown in the dotted lines in Figures 4, 7 and 8.

A radial slot 45 is formed in the cylindrical end portion of the shaft 43. Said slot forms a 60 means for slidably mounting the vane 46, which is substantially rectangular in shape except for a cut-off corner within the slot 45 to correspond to an arcuate end wall of said slot. A compression spring 47, seated in aligned bores in 65 the vane 46 and in the enlarged end portion of

the shaft 43, urges the vane 46 radially outwardly, whereby it is maintained in contact with the cylindrical wall of the chamber 39. The contacting end of the vane, as well as the edges and faces within the slot 45, are closely and accurately fitted to provide for a substantially fluid-tight seal between the two compartments formed on opposite sides of the vane. 5

At one portion of the upper side of the casing 28 a substantially circular, flat face 48 is formed 10 to provide a seat for a valve casing 49. Said casing houses a rotatable valve member 50, which is operable from a shaft 51 by a non-rotatable connection between the shaft and the valve member. An operating handle 52 is non-rotatably secured to the upper end of the shaft 51 outside the casing. Suitable packing may be provided for preventing the escape of liquid around the shaft 51.

A pressure spring 53 is positioned to abut the 20 valve member 50 and hold it against the seat 48. To provide means for balancing the valve member, an opening 54 communicates with the high pressure chamber 29 and with the space 55 above the valve member. 25

The valve member 50 is provided with two arcuate recesses 56 and 57 positioned diametrically opposite each other, the two slots occupying substantially all of the face of the valve member. A passage-way 58 connects the high pressure 30 chamber 29 with the valve member 50, being in communication with either of the recesses positioned over said passage-way. A second passage-way 59 communicating with the seat 48, on which the valve member is mounted, extends 35 vertically downwardly and through a cored passage 60 at the base of the housing 28, terminating, as shown in Figure 6, adjacent one end of the semiannular chamber 39 in which the vane 46 oscillates. 40

It will be understood that, with the valve member 50 in the position shown in Figure 4, fluid under pressure is conducted through the passage-way 58, the recess 57, the passage-way 59 and the passage-way 60 into the chamber 39. 45 If the vane is in the dotted position shown in Figure 7, pressure is then applied to the vane, rotating it about its mounting axis in a clockwise direction. At the same time, liquid at the other side of the vane escapes through a passage-way 61 similar to the passage-way 60, which communicates with the chamber 39 in a corresponding position at its other end. As shown in Figure 5 and in dotted lines in Figure 4, the passage-way 61, which is cored in the base of the 55 housing 28, communicates with a vertical conduit 62 communicating with the seat 48 over which the valve member 50 is mounted. With the valve member in the position shown in Figure 4, fluid escaping through the vertical conduit 62 passes through the recess 56 and downwardly through an opening 63 communicating with the reservoir 38. This illustrates a complete 60 circuit of the liquid during the lifting operation.

It will be understood that by shifting the valve 65 member 50 approximately 90 degrees, the high pressure liquid is delivered to the conduit 61 at the opposite side of the vane 46 and that the low pressure liquid on the other side of the vane in that position escapes through the passage-way 70 60, through the recess 56, which would then be in communication with the vertical conduit 59 and would escape back into the reservoir through the opening 63.

The above description of the parts referred to 75

and designated by numerals was made with simultaneous explanation of the operation of the device of which said elements described are parts. There is another important feature which will now be described.

As the vane 46 completes its stroke, as the operation of a hydraulic device may be termed, the vane being in effect a hydraulically operated piston, stops 64 are provided which engage the base 27 below the housing 28. As the vane passes into this position, a liquid conduit 66 formed in the cylindrical portion of the shaft 43 within the chamber 39 is brought into communication through a bore 67 with a by-pass opening 68 formed in the wall between the chamber 39 and the reservoir 38. Liquid thereafter supplied through the conduit 60—considering the vane as being in the position shown in Figure 7—is by-passed back into the reservoir through the conduit 66, the bore 67 and the by-pass opening 68. A corresponding conduit 66' and a bore 67' are formed at the other side of the vane to similarly by-pass liquid under pressure supplied through the passage-way 61 when the vane is in the dotted position indicated in Figure 7. It will be understood that, by the provision of a by-pass arrangement as described, it is only necessary for the operator to shift the valve into either one of the two positions, there being no provision for a neutral position. The vane is then rotated to its end position, after which liquid is by-passed with no appreciable back pressure. When it is desired to rotate the lifting shafts 43 and 44 in the other direction, the valve member 50 is shifted 90 degrees, whereby the vane 46 is moved angularly to its other end position.

It will be noted that substantially more than 180 degrees angular movement has been provided for the vane 46 in the annular chamber 39. This provision has been made particularly for use of the device in connection with the lifting of field implements. Referring to Figure 1, the projecting end of the shaft 43 visible in that figure carries a lifting member 69 which is provided with a plurality of circumferentially spaced openings 70. A crank pin 71 mounted in one of these openings forms a pivotal support for a rearwardly extending lifting link 72 and a forwardly extending lifting link 73. The shaft 42 is provided with the same lifting connections. It will be noted that with the implements lifted as represented in this figure of the drawings, the pin 71 is past dead center with respect to the axis of the lifting shaft 43. As the forward lifting member 73 is a compression member and as the rear lifting link 72 is a tension member, the weight of the implements acts to hold the lifting device locked in this past dead center position. When the vane is oscillated to its other extreme position, the pin 71 will be past dead center at the other side of the axis of the shaft 43. In this position, with the implements lowered, the member 72 becomes a compression member and the member 73 becomes a tension member. It is, therefore, to be understood that in this position the pressure of the implements also tends to hold the lifting device locked in its over-dead-center position. This description is given as one embodiment in which the inherent property of applicant's device in permitting over-dead-center in two positions may be utilized to great advantage. In either of these positions the vane is abutting the stops provided and there is no tendency for the lifting device to leave its posi-

tion. Moreover, at the end of the stroke in each direction the vane is moved by the force of the lifting connections to complete its stroke and to put the by-pass communications into operation, whereby pressure is released. Due to this principle of operation there is practically no back pressure exerted on the pumping system, requiring substantially no power and resulting in very little wear upon the pump gears or upon the chain of the driving gears therefor.

Although applicant has shown and described his improved hydraulic lifting device as located in a preferred position on a tractor and as operating lifting means for implements located in certain positions, it is to be understood that he claims as his invention all modifications in the construction of the lifting mechanism, its location on a tractor, and its use in connection with different types of lifting connections and different implements which may be covered by the appended claims.

What is claimed is:

1. A power lift device for tractors comprising, in combination with a tractor and an implement connected thereto, a transverse rock-shaft mounted on the tractor, lifting connections between the rock-shaft and the implement, a lifting shaft mounted on the tractor spaced longitudinally from the rock-shaft, a lifting lever on the rock-shaft, a lifting crank on the lifting shaft, a lifting member connecting said crank and said lever, a casing into which the lifting shaft extends, a vane secured to said shaft within the casing, and means to apply pressure to either side of the vane whereby the lifting shaft may be rotated in opposite angular directions.

2. A power lift device for tractors comprising, in combination with a tractor and an implement connected thereto, a transverse rock-shaft mounted on the tractor, lifting connections between the rock-shaft and the implement, a lifting shaft mounted on the tractor spaced longitudinally from the rock-shaft, a lifting lever on the rock-shaft, a lifting crank on the lifting shaft, a lifting member connecting said crank and said lever, a casing into which the lifting shaft extends, a vane secured to said shaft within the casing, and means to apply pressure to either side of the vane whereby the lifting shaft may be rotated in opposite angular directions, said means being effective to move the vane substantially more than 180 degrees in each angular direction.

3. A power lift device for tractors comprising, in combination with a tractor and an implement connected thereto, a transverse rock-shaft mounted on the tractor, lifting connections between the rock-shaft and the implement, a lifting shaft mounted on the tractor spaced longitudinally from the rock-shaft, a lifting lever on the rock-shaft, a lifting crank on the lifting shaft, a lifting member connecting said crank and said lever, a casing into which the lifting shaft extends, a vane secured to said shaft within the casing, and means to apply pressure to either side of the vane whereby the lifting shaft may be rotated in opposite angular directions, said means being effective to move the vane substantially more than 180 degrees in each angular direction, the lifting crank being positioned relative to the vane to be moved past dead center with respect to a center line from the axis of the lifting shaft to the connection point of the lifting member with the lifting lever on the rockshaft.

4. A power lift device for tractors comprising, in combination with a tractor and an implement

- connected thereto, a transverse rock-shaft mounted on the tractor, lifting connections between the rock-shaft and the implement, a lifting shaft mounted on the tractor spaced longitudinally from the rock-shaft, a lifting lever on the rock-shaft, a lifting crank on the lifting shaft, a lifting member connecting said crank and said lever, a casing into which the lifting shaft extends, a vane secured to said shaft within the casing, means for supplying fluid under pressure to either side of the vane, and means operable by movement of the vane at a predetermined angular position to reduce the application of pressure thereto.
15. 5. A power lift device for tractors comprising, in combination with a tractor and an implement connected thereto, a transverse rock-shaft mounted on the tractor, lifting connections between the rock-shaft and the implement, a lifting shaft mounted on the tractor spaced longitudinally from the rock-shaft, a lifting lever on the rock-shaft, a lifting crank on the lifting shaft, a lifting member connecting said crank and said lever, a casing into which the lifting shaft extends, a vane secured to said shaft within the casing, means for supplying fluid under pressure to either side of the vane, and means operable by movement of the vane at a predetermined angular position to reduce the application of pressure thereto and to hold the vane in that position.
6. In a tractor having a housing at the rear thereof containing driving gearing, said housing having an opening normally closed by a cover-plate and, in combination therewith; a power lift casing secured to the housing over said opening, a transverse lifting shaft extending into said casing, a hydraulic device in the casing connected to the lifting shaft for transmitting angular movement to the shaft, a liquid pump mounted on the housing adapted to be driven by the gearing within the housing, and means for conducting fluid under pressure from the pump to the casing for actuating the hydraulic device to rotate the lifting shaft in either direction.
45. 7. In a tractor having a housing at the rear thereof containing driving gearing, said housing having an opening normally closed by a cover-plate and, in combination therewith; a power lift casing secured to the housing over said opening, a transverse lifting shaft extending into said casing, a hydraulic device in the casing connected to the lifting shaft for transmitting angular movement to the shaft in either direction, a liquid pump mounted on the housing adapted to be driven by the gearing within the housing, and means for conducting fluid under pressure from the pump to the casing for actuating the hydraulic device.
8. In a tractor having a housing at the rear thereof containing driving gearing, said housing having an opening normally closed by a cover-plate and, in combination therewith; a power lift casing secured to the housing over said opening, a transverse lifting shaft extending into said casing, a hydraulic device in the casing including a vane directly connected to the lifting shaft for transmitting angular movement to the shaft in either direction, a liquid pump mounted on the housing adapted to be driven by the gearing within the housing, and means for conducting fluid under pressure from the pump to the casing for actuating the hydraulic device.
9. In a tractor having a housing at the rear thereof containing driving gearing, said housing having an opening normally closed by a cover-

plate and, in combination therewith, a power lift casing secured to the housing over said opening, a transverse lifting shaft extending into said casing, a hydraulic device in the casing connected to the lifting shaft for transmitting angular movement to the shaft, a liquid pump mounted on the housing adapted to be driven by the gearing within the housing, and means for conducting fluid under pressure from the pump to the casing for actuating the hydraulic device to rotate the lifting shaft in either direction, said means being operative to supply fluid continuously and said hydraulic device including means operative to render the device ineffective when a predetermined location is reached in the angular movement of the shaft.

10. A hydraulically operated power lift for tractor connected implements comprising a housing mounted on the tractor, a transverse shaft extending through said housing, means for connecting a lifting member to said shaft outside the housing, a substantially semicylindrical chamber formed in the housing around the shaft, a vane secured to said shaft for angular movement therewith in the chamber, means for supplying fluid under pressure to the semicylindrical chamber at each side of the vane adjacent the bottom of the chamber, whereby the vane may be moved in opposite angular directions, and by-pass means operated by movement of the vane to by-pass fluid when the vane has reached its maximum position in either angular direction.

11. A hydraulically operated power lift for tractor connected implements comprising a housing mounted at the rear of the tractor, a transverse shaft extending through said housing, means for connecting a lifting member to said shaft outside the housing, a substantially semicylindrical chamber formed in the housing around the shaft, a vane secured to said shaft for angular movement therewith and fitted in a substantially fluid-tight manner in the semicylindrical chamber, a liquid pump mounted on the tractor and driven from the tractor engine, a valve chamber mounted on the tractor, fluid conduits connecting the pump, the valve chamber and the housing, two of said conduits being formed to communicate with the semicylindrical chamber at each side of the vane adjacent the bottom of the chamber, said valve being operated to deliver fluid under pressure to either of said conduits whereby the vane may be moved in opposite angular directions, and by-pass means operated by movement of the vane to by-pass fluid when the vane has reached its maximum position in either angular direction.

12. A hydraulically operated power lift for tractor connected implements comprising a housing mounted at the rear of the tractor, a transverse shaft extending through said housing, means for connecting a lifting member to said shaft outside the housing, a chamber formed in the housing as a portion of a cylinder with the shaft as an axis, a vane secured to said shaft for angular movement of substantially more than 180 degrees in the chamber and fitted in a substantially fluid-tight manner therein, means for supplying fluid under pressure to the chamber at each side of the vane whereby the vane may be moved in opposite angular directions, and by-pass means operated by movement of the vane to by-pass fluid when the vane has reached its maximum position in either angular direction.

13. A hydraulically operated power lift for tractor connected implements comprising a housing mounted at the rear of the tractor, a transverse shaft extending through said housing, 5 means for connecting a lifting member to said shaft outside the housing, a chamber formed in the housing as a portion of a cylinder with the shaft as an axis, a vane secured to said shaft for angular movement of substantially more than 180 degrees in the chamber and fitted in a substantially fluid-tight manner therein, a liquid pump mounted on the tractor and driven from the tractor engine, a valve chamber mounted on the tractor, fluid conduits connecting the pump, the 10 valve chamber and the housing, two of said conduits being formed to communicate with the semicylindrical chamber at each side of the vane adjacent the bottom of the chamber, said valve being operated to deliver fluid under pressure to either of said conduits whereby the vane may be moved in opposite angular directions, and by-pass means operated by movement of the vane to by-pass fluid when the vane has reached its maximum position in either angular 15 direction.

14. A hydraulically operated power lift for tractor connected implements comprising, in combination with a tractor, a housing mounted on the tractor, a shaft extending into said housing, means for connecting a lifting member to said shaft outside the housing, a substantially semicylindrical chamber formed in the housing around the shaft, a vane secured to said shaft for angular movement therewith and fitted in a substantially fluid-tight manner in the chamber, a liquid pump mounted on the tractor and driven from the tractor engine, a valve chamber mounted on the tractor, fluid conduits connecting the pump, the valve chamber and the housing, one 30 of said conduits being formed to communicate with the semicylindrical chamber at each side of the vane adjacent the bottom of the chamber, said valve being operated to deliver fluid under pressure to either side of the vane, and by-pass means operated by movement of the vane to by-pass fluid when the vane has reached its maximum position in either angular 35 direction.

15. A power lift device for tractors comprising, in combination with a tractor and an implement connected thereto, a rockshaft mounted on the tractor, lifting connections between the rockshaft and the implement, a lifting shaft mounted on the tractor spaced from the rockshaft, a lifting lever on the rockshaft, a lifting crank on the lifting shaft, a lifting member connecting said crank and said lever, a casing into which the lifting shaft extends, a vane secured to said shaft within the casing, and means to apply fluid pressure against the vane.

16. A power lift device for tractors comprising, in combination with a tractor and an implement connected thereto, a rockshaft mounted on the tractor, lifting connections between the rockshaft and the implement, a lifting shaft mounted on the tractor spaced from the rockshaft, a lifting lever on the rockshaft, a lifting crank on the lifting shaft, a lifting member connecting said crank and said lever, a casing into which the lifting shaft

extends, a vane secured to said shaft within the casing for an angular movement of substantially more than 180°, and means to apply fluid pressure against either side of the vane whereby the lifting shaft may be rotated in opposite angular directions, said means being effective to move the vane substantially more than 180° in each angular direction.

17. A power lift device for tractors comprising, in combination with a tractor and an implement connected thereto, a rockshaft mounted on the tractor, lifting connections between the rockshaft and the implement, a lifting shaft mounted on the tractor spaced from the rockshaft, a lifting lever on the rockshaft, a lifting crank on the lifting shaft, a lifting member connecting said crank and said lever, a casing into which the lifting shaft extends, a vane secured to said shaft within the casing, and means to apply pressure to either side of the vane whereby the lifting shaft may be rotated in opposite angular directions, said means being effective to move the vane substantially more than 180° in each angular direction, the lifting crank being positioned relative to the vane to be moved past dead center with respect to a center line from the axis of the lifting shaft to the connection point of the lifting member with the lifting lever on the rockshaft.

18. A power lift device for tractors comprising, in combination with a tractor and an implement connected thereto, a lifting shaft mounted on the tractor, a lifting crank on the lifting shaft, means for connecting said crank to the implement, a casing into which the lifting shaft extends, a vane secured to said shaft within the casing, means for supplying fluid under pressure to either side of the vane, and means operable by movement of the vane at a predetermined angular position to reduce the supply of fluid thereto.

19. A power lift device for tractors comprising, in combination with a tractor and an implement connected thereto, a lifting rockshaft associated with the implement, a lifting shaft mounted on the tractor, a lifting lever on the rockshaft, a lifting crank on the lifting shaft, a casing into which the lifting shaft extends, a vane secured to said shaft within the casing, means for supplying fluid under pressure to either side of the vane, and means operable by movement of the vane at a predetermined angular position to reduce the supply of fluid thereto.

20. A hydraulically operated power lift for tractor connected implements comprising a housing mounted on the tractor, a shaft extending through said housing, means for connecting a lifting member to said shaft outside the housing, a substantially semicylindrical chamber formed in the housing around the shaft, a vane secured to said shaft for angular movement therewith in the chamber, means for supplying fluid under pressure to the semicylindrical chamber at one side of the vane adjacent the bottom of the chamber, whereby the vane may be moved in an angular direction, and by-pass means operated by movement of the vane to by-pass fluid when the vane has reached its maximum position.

EDWARD A. JOHNSTON.
